(57) **CLAIM**

The ornamental design for a display screen or portion thereof with graphical user interface, as shown and described.

DESCRIPTION

This application is a continuation of and claims priority to U.S. Design application Ser. No. 29/675,929, filed Jan. 7, 2019, which is a continuation of Design application Ser. No. 29/644,207, filed Apr. 16, 2018, which is a continuation of Design application Ser. No. 29/576,400, filed Sep. 2, 2016, which is a continuation of Design application Ser. No. 29/541,032, filed Sep. 30, 2015, which is a continuation of Design application Ser. No. 29/538,921, filed Sep. 9, 2015, which is a continuation of Design application Ser. No. 29/457,353, filed Jun. 9, 2013. Each of these applications is incorporated herein in its entirety by reference thereto. The FIGURE is a front view of a display screen or portion thereof with graphical user interface showing the claimed design.

The outermost broken lines in the FIGURE show a display screen or portion thereof and form no part of the claimed design. The other broken lines in the FIGURE show portions of the graphical user interface that form no part of the claimed design.

1 Claim, 1 Drawing Sheet

Related U.S. Application Data

Aug. 31, 2016, now Pat. No. Des. 786,294, which is a continuation of application No. 29/541,140, filed on Sep. 30, 2015, now Pat. No. Des. 768,181, which is a continuation of application No. 29/457,361, filed on Jun. 10, 2013, now Pat. No. Des. 741,350, said application No. 29/576,140 is a continuation of application No. 29/541,138, filed on Sep. 30, 2015, now Pat. No. Des. 765,711, which is a continuation of application No. 29/457,361, filed on Jun. 10, 2013, now Pat. No. Des. 741,350.
